JOHN C. BLACK, OF LOS ANGELES, CALIFORNIA

PROCESS FOR DISTILLING AND CRACKING PETROLEUM OILS

Application filed October 8, 1928. Serial No. 311,140.

This invention relates to a process for distilling and cracking petroleum oils for the production of a maximum percentage of gasoline stock and the production of a marketable fuel oil which will be suitable for bunker fuel oil "C", as specified in the Bureau of Mines Technical Paper 323 B.

This process consists first in the separation by distillation and fractionation from crude petroleum oils, the natural occurring gasoline stock and a higher boiling distillate which I denominate "light gas oil" and a residual oil to be further processed; then separately separating by a second distillation and fractionation a synthetic gasoline stock derived from a cracking operation, a cracked light gas oil stock, and a distillate which I denominate "heavy gas oil" and a residual oil to be further processed; the "heavy gas oil" above referred to is a blend of distillates, one portion being obtained from the original crude petroleum and a second portion being obtained from the cracking steps. The residual oil derived from the second distillation step is now subjected to a cracking operation, said operation producing a cracked gasoline stock and a heavy gas oil distillate. This heavy gas oil distillate is blended with the previously produced "heavy gas oil" of the second distillation step. The residual oil separated by distillation after the aforesaid cracking operation is blended with the light gas oil or the light cracked gas oil produced in the first or second distillation step.

By well-known processes, when the maximum yield of distillate suitable for the production of synthetic gasoline stock is separated from a crude petroleum oil by distillation, the residual oil is too viscous to be suitable for marketable fuel oil, such as bunker fuel oil "C", while by my process, this difficulty is overcome by a further cracking treatment of the residual oil in which a cracked naphtha is produced and a heavy gas oil stock suitable for the production of synthetic gasoline is also produced and a residual oil which when commingled with the light gas oil obtained by the first or second distillation operation, will

reduce the viscosity of said residual oil to the desired degree.

It is well-known in the art of cracking petroleum oil distillates that the lower boiling fractions which I have denominated "light gas oil" fractions are less desirable for cracking since a higher temperature and higher pressure is required to maintain the lower boiling fractions in the liquid phase and the synthetic gasoline produced has too high a percentage of boiling point stock in the upper range of the gasoline fraction, making a gasoline stock defective in the initial, the 10, 20 and 30 per cent fractions thereby making a gasoline with poor starting and poor anti-knock qualities. Also due to the higher temperature and pressure required, there is a more rapid destruction of the cracking equipment. Therefore, by my invention, these lower boiling hydrocarbons which I have termed "light gas oil" having boiling points ranging from approximately 400 to 550 degrees F. are separated from the gasoline boiling point stock and the higher boiling point distillates or heavy gas oil stock and may be subsequently employed for reducing the viscosity of the final residual oil. I am aware that methods are now well-known in the art for reducing the viscosity of viscous petroleum oils by the addition of less viscous distillates thereto, produced by a partial distillation of the viscous oil, or by the addition of less viscous oil obtained from other sources, or by heating the petroleum oil to a relatively high temperature while passing through a heating coil under pressure and then cooling the oil before any substantial cracking takes place.

By my improved process, the yield of a desirable heavy gas oil stock suitable for thermo cracking is increased as much as 20 per cent or more over the well-known methods for obtaining a gas oil stock for the same purpose, and at the same time producing a fuel oil with a sufficiently low viscosity to be marketable as bunker fuel oil "C", or other fuel oils with a lower viscosity, depending upon the amount of light gas oil stock used for reducing the viscosity.

An object of the invention is to produce from crude petroleum oil a maximum yield

of gasoline boiling point stock and under certain conditions a lamp oil stock and a residual oil which will have a viscosity sufficiently low to meet the requirements as specified for 5 bunker fuel oil "C", in the Bureau of Mines Bulletin 323 B.

Another object of the invention is to produce a maximum percentage of gas oil stock suitable for the production of synthetic gaso- 10 line and a residual fuel oil of marketable value.

Another object of the invention is to provide a process to utilize the light gas oil fraction derived either from crude petroleum oil 15 by distillation, or derived by distillation of cracked petroleum oils to reduce the viscosity of the final residual heavy oil.

Another object of the invention is to provide a process to produce a maximum yield 20 of gasoline boiling point stock, both natural and synthetic; a light gas oil fraction and a marketable fuel oil from a crude petroleum oil by a sequence of operations, consisting in first separately separating by distillation and 25 fractionation the natural gasoline stock and a higher boiling distillate or light gas oil stock derived from the crude oil distillation step of the process, then separately separating by a second distillation and fractionation 30 operation, a higher boiling distillate or heavy gas oil stock; a synthetic gasoline stock and a cracked light gas oil stock, both being derived from an introduced cracked petroleum oil, said introduced cracked oil stock being 35 simultaneously and independently produced by cracking the heavy gas oil stock collected from the various distillation steps of the process; there is also produced in the second distillation step a residual oil which is then 40 cracked in a separate cracking step producing a synthetic gasoline stock and a heavy gas oil stock suitable for subsequent cracking and a final residual oil, the viscosity of which is reduced by commingling the same with the 45 light gas oil separated in the first or second distillation operation.

Another object of the invention is to provide a process wherein the natural and synthetic gasolines are independently and sep- 50 arately collected, for the reason that the synthetic gasoline requires a different subsequent treatment than the natural gasoline.

Another object of this invention is to provide a process wherein a uniform heavy gas 55 oil or cracking product is obtained by blending the heavy gas oil fractions derived from the various distillation steps.

With the foregoing preliminary explanation, the preferred embodiment of my invention 60 will now be more fully explained by reference to the accompanying drawing which illustrates a special form of apparatus which may be utilized in carrying out the objects of the present invention.

65 In the drawing, 1 represents generally a

tank for holding the crude petroleum oil to be treated. Pipe 2 connects the tank 1 to the inlet side of pump 3. Pipe 4 connects the discharge side of pump 3 to heat exchanger 5. Pipe 6 connects the heat exchanger 5 to heat 70 exchanger 7. Pipe 8 connects the heat exchanger 7 to heat exchanger 31. Pipe 104 connects the heat exchanger 31 to vapor separator 106. Vapor separator 106 is provided with overflow trays 105. Pipe 85 connects 75 the vapor separator 106 to fractionating tower 88. Pipe 103 controlled by a valve connects vapor separator 106 to the suction side of pump 102. Pipe 101 connects the discharge side of pump 102 to heater coil 100. The heater coil 100 is stationed in the upper part of furnace 95. The furnace 95 is provided with a burner 95'. Pipe 98 connects the heater coil 80 to fractionating tower 88. The fractionating tower 88 is provided with a steam spray pipe 82 which leads to a source of steam not shown, so that steam may be introduced into the fractionating tower 88 at the bottom during the distillation operation, if desired. The fractionating tower 88 is provided with bubble caps 83 and 86 and a separator plate 84. A pipe 87 connects fractionating tower 88 to a dephlegmator 90. The dephlegmator 90 is provided with a liquid inlet pipe 89" leading 85 to a source of water or oil not shown, which is connected to tubes 89' for conveying a cooling medium through the dephlegmator 90. Dephlegmator 90 is also provided with liquid outlet pipe 89. A pipe 91 connects the dephlegmator 90 to condenser coil 92. The condenser coil 92 is stationed in the condenser box 96. Pipe 93 connects condenser coil 92 to a naphtha storage tank 109. Pipe 90' controlled by a valve, connects the naphtha storage tank 109 at the bottom and leads to a 90 source of storage not shown. Pipe 93' is connected to the pipe 93 and leads to a gas storage not shown. Pipe 99 connects the fractionating tower 88 to heat exchanger 5. Pipe 81 controlled by the valve 81' connects the 100 fractionating tower 88 at the bottom to the inlet side of pump 80. A pipe 77 connects the discharge side of pump 80 to heater coil 76. The heater coil 76 is stationed in the furnace 79 which is provided with a burner 78. Pipe 75 controlled by valve 75' connects the heater coil 76 to fractionating tower 59. The fractionating tower 59 is provided with bubble caps 57 and 70, separator plates 58 and 58', and a steam spray line 56. The steam spray line 56 leads to a source of steam not shown. The fractionating tower 59 is connected to dephlegmator 59'. Dephlegmator 59' is provided with a liquid inlet pipe 72 and a liquid outlet pipe 73. Pipe 63 connects the fractionating tower 59 at the top to condenser coil 62, which is stationed in the condenser box 61 and is connected to synthetic naphtha tank 64 by pipe 61'. A pipe 62' is connected 110 to the pipe 61' and leads to an absorber not 115 connected to the pipe 61'. A pipe 62' is connected to the pipe 61' and leads to an absorber not 120 connected to the pipe 61'. A pipe 62' is connected to the pipe 61' and leads to an absorber not 125 connected to the pipe 61'. A pipe 62' is connected to the pipe 61' and leads to an absorber not 130

shown. Pipe 55 connects the fractionating tower 59 just above the separator plate 58 to heat exchanger 7. Pipe 129, controlled by a valve, connects the fractionating tower 59 just above the separator plate 58' to light gas oil tank 130. Pipe 131, controlled by a valve, connects the light gas oil tank 130 to the suction side of pump 133. Pipe 132, controlled by a valve, connects the discharge side of pump 133 to pipe 124. Pipe 54 controlled by the valve 54', connects the fractionating tower 59 at the bottom to the inlet side of pump 53. Pipe 51, controlled by valve 51' connects the discharge side of pump 53 to heater coil 50. The heater coil 50 is stationed in the furnace 49 provided with a burner 52. Pipe 47 controlled by pressure regulating and discharge valve 48, connects the heater coil 50 to the fractionating tower 11. The fractionating tower 11 is provided with tile or checker brick work 21, bubble caps 19 and a separator plate 22. Pipe 12 connects fractionating tower 11 at the top to condenser coil 13 which is stationed in the condenser box 14. Pipe 15 connects the condenser coil 13 to a synthetic naphtha tank 16. 17 is a pipe controlled by a valve connected to the bottom of the synthetic naphtha tank 16 and leads to a source of storage not shown. Pipe 28 controlled by a valve, connects the fractionating tower 11 at the bottom to the inlet side of pump 27. Pipe 30 connects the discharge side of pump 27 to heat exchanger 31. Pipe 32 connects the outlet side of heat exchanger 31 to cooler 33. Pipe 34 connects the cooler 33 to residual oil tank 35. Pipe 36 controlled by valve 110 is an outlet pipe leading to a source of storage not shown.

123 is a pipe which connects heat exchanger 5 to light gas oil tank 127. Pipe 128 controlled by a valve, is connected to light gas oil tank 127 and leads to a source of storage not shown. 126 is a pipe connecting the light gas oil tank 127 at the bottom to the inlet side of pump 125. 124, controlled by the valve 124', is a pipe connecting the discharge side of pump 125 to the inlet side of pump 27. 74 is a pipe connecting heat exchanger 7 to heavy gas oil tank 68. 41 is a pipe connecting the heavy gas oil tank 68 to the inlet side of pump 42. Pipe 43 connects the discharge side of pump 42 to pipes 46 and 20 controlled by valves 44 and 45. Pipe 10 connects fractionating tower 11 above the separator plate 22 to the cooler 111. Cooler 111 is provided with a water inlet pipe 108' which leads to a source of cooling water not shown and water outlet pipe 108 which leads to a source of waste not shown. 38 is a pipe connecting the cooler 111 to the top of heavy gas oil tank 68. Pipe 69 controlled by valve 67' connects the heavy gas oil tank 68 at the bottom to the inlet side of pump 66. Pipe 65, controlled by valve 65' connects the discharge side of pump 66 to heat exchanger 9.

Pipe 118 connects the heat exchanger 9 to heater coil 116. Pipe 120 connects heater coil 116 to pipe 121. The pipe 121 is provided with a valve 121'. Branch pipe 122 controlled by valve 122' connects the pipe 65 to pipe 118. Branch pipe 117 controlled by valve 117' connects pipe 65 to heater coil 116 which is employed for the introduction of cool oil into the hot oil stream as it leaves the heater coil 116. The heater coil 116 is stationed in the furnace 114 provided with a burner 115. Pipe 9' controlled by a valve, connects a source of water or steam not shown to pipe 118. Pipe 37, controlled by a pressure regulating and discharge valve 37' connects the heat exchanger 9 to fractionating tower 59.

The preferred process as carried out with the apparatus just described is as follows:

Crude petroleum oil contained in the tank 1 is caused to flow through the pipe 4 by operating pump 3, which takes suction on the crude oil tank 1 through the pipe 2. From pipe 4 the crude petroleum oil passes through heat exchangers 5, 7 and 31 which are connected by pipes 6 and 8. The crude petroleum oil passing through said heat exchangers 5, 7 and 31 undergoes a heat exchange with the hot distillates coming from fractionating towers 88 and 59 and the residual oil coming from the bottom of the fractionating tower 11. By this exchange, the crude petroleum oil is preheated to a temperature of approximately 200 to 300 degrees F. From the heat exchanger 31, the preheated crude petroleum oil passes through the pipe 104 into vapor separator 106 flowing over plates 105. The vaporized hydrocarbons produced by this heat exchange pass out of the separator 106 through the pipe 85 and into the middle section of fractionating tower 88 and are thereafter condensed and collected along with other gasoline boiling point stock. From the vapor separator 106, the crude petroleum oil, separated from the vapors produced by the said heat exchange, passes through the pipe 103 into the suction side of pump 102 which discharges the same through the pipe 101 and then through the heater coil 100. The heater coil 100 is maintained at a temperature sufficient to raise the temperature of the oil to approximately 450 to 600 degrees F. by means of burner 95' which is stationed near the bottom of the furnace 95. From heater coil 100 the heated oil passes through pipe 98 and into the lower section of fractionating tower 88 where a fractional separation of the lower boiling hydrocarbons is effected, the distillation being assisted by the injection of steam from steam spray line 82. The vaporized hydrocarbons pass up through the bubble caps 83 and then through the separator plate 84 and are thereafter further fractionated on passing through the bubble caps 86 and dephlegmator 90, by reg-

ulation of which, gasoline boiling point stock or naphtha is separated from a higher boiling distillate or light gas oil. The gasoline boiling point stock passes from dephlegma-
5 tor 90 into pipe 91 and is condensed as it passes through the condenser coil 92. The condensed gasoline boiling point stock is collected in the naphtha receiving tank 109. The temperature of the oil vapors passing
10 through the dephlegmator 90 is controlled by the introduction of a regulated supply of oil or water which passes through the pipe 89'' and then through the tubes 89' and out through the pipe 89 to a storage not shown.
15 The higher boiling distillate which I have denominated "light gas oil" separated and condensed by the fractionation operation in the upper section of the said fractionating tower 88, passes into pipe 99 and then
20 through the heat exchanger 5 where the temperature is reduced by a heat exchange with the cool crude petroleum oil coming from the crude oil tank 1. From heat exchanger 5 the light gas oil passes through pipe 123 and then
25 into the light gas oil tank 127. By opening valve 126' the light gas oil may be permitted to flow into the suction side of pump 125 which discharges the same into pipe 124. From pipe 124 the light gas oil passes into
30 the suction side of pump 27, the flow being regulated by valve 124'. The light gas oil passing into pump 27 mixed with the light gas oil from tank 130, is commingled with the residual oil coming from the bottom of
35 fractionating tower 11 through pipe 28, the flows being regulated so as to produce a fuel oil with a desired viscosity. In case an excess of light gas oil collects in the tank 127 it may be conducted to a storage not shown through
40 the pipe 128 controlled by a valve and thereafter treated for lamp oil or other uses. Pump 27 discharges the said commingled light gas oil and residual oil or fuel oil, through the pipe 30, heat exchanger 31, pipe
45 32, cooler 33, pipe 34, and then into the residual oil tank 35. From the residual oil tank 35 a fuel oil having a desired viscosity may be conducted to a storage not shown, by opening the valve 110, which permits the fuel oil to
50 flow into pipe 36. The residual oil as it collects in the bottom of fractionating tower 88 passes into pipe 81, the flow being regulated by operating valve 81'. From pipe 81 the residual oil passes into the suction side of
55 pump 80 which discharges the same in a regulated continuous flow through pipe 77 and heater coil 76. The burner 78 which is stationed in the lower section of furnace 79, is regulated so that the residual oil passing
60 through the heater coil 76 will be heated to a temperature of approximately 550 to 650 degrees F., the regulation of this temperature depending upon the rate of flow, the quality of the residual oil and the per cent of
65 distillate or heavy gas oil stock desired.

From heater coil 76 the hot residual oil passes through pipe 75 and then into the lower section of fractionating tower 59, the rate of flow being regulated by operating valve 75'. The fractionating tower 59 is provided with a steam spray pipe 56 which leads to a source of steam not shown by means of which steam in desired amounts may be introduced into the said fractionating tower to assist the distillation operation. The fractionating tower 59 is provided with bubble caps 57, a separator plate 58, an upper set of bubble caps 70, an upper separator plate 58' and a dephlegmator 59'.
75

Cracked petroleum oil produced by continually cracking the heavy gas oil as it collects in the heavy gas oil tank 68, is continuously introduced into the bottom of the fractionating tower 59, coming through pipe 37, controlled by the pressure regulating and discharge valve 37', and is therein fractionated together with said heated oil coming from the heater coil 76, as heretofore described. In the fractionating tower 59 the gasoline boiling point stock contained by the introduced cracked petroleum oil is vaporized and fractionally separated from a light cracked gas oil stock, the light cracked gas oil stock passing out through the pipe 129 and then into the light gas oil tank 130.
90
95

The vaporized synthetic gasoline boiling point stock passes from the fractionating tower 59 through dephlegmator 59', pipe 63, condenser coil 62 and is collected in the synthetic naphtha tank 64. The higher boiling point stock, or heavy gas oil stock, which is condensed in the fractionating tower 59, passes through the pipe 55, heat exchanger 7, pipe 74 and then into the heavy gas oil tank 68. The residual oil which collects in the bottom of fractionating tower 59 below the separator plate 58, passes out through the pipe 54 and into the suction side of pump 53, the flow being controlled by valve 54'. Pump 53 discharges this hot residual oil through the pipe 51 controlled by valve 51' and then through the heater coil 50 at a pressure sufficient to prevent any substantial vaporization thereof, approximately 450 to 1000 pounds. A burner stationed in the lower part of furnace 49 is so regulated that the residual oil passing through the heater coil 50 will attain a temperature from 700 to 900 degrees F., the regulation of this temperature depending upon the rate of flow, the viscosity of the residual oil and the amount of cracking desired. As the residual oil leaves the heating coil 50 at a cracking temperature, a cooler oil distillate coming through the pipe 46 from the heavy gas oil tank 68 is introduced into the pipe 47 in quantities sufficient to lower the temperature of the mixed oil below a cracking temperature. From the pipe 47 the mixed oils pass through pressure regulating and discharge valve 48 and then into the lower section
100
105
110
115
120
125
130

of fractionating tower 11, wherein the pressure is reduced to approximately normal. In fractionating tower 11, the introduced hot oil at a temperature of approximately 750 degrees F. is subjected to a fractionating and washing operation by the continuous introduction of a wash oil from heavy gas oil tank 68. The wash oil passes from the heavy gas oil tank 68 through pipe 41 into the suction side of pump 42 which discharges the same through pipe 43 and pipe 20 which ends in a spray pipe as shown, the flow being controlled by valve 44. A part of the flow of oil passing through the pipe 43 enters the branch pipe 46, the flow being controlled by the valve 45 and is introduced into the hot flow of oil coming through the pipe 47 as heretofore described. The oil which passes through pipe 20 is employed as a wash oil to condense and dissolve the higher boiling distillates produced by the cracking of the residual oil. The wash oil passes from pipe 20 through a spray pipe stationed between the bubble caps 19 and the checker brick work or spaced tile 21. The wash oil after passing over the spaced tile 21 passes down to the separator plate 22 together with the condensed distillate, and then through the pipe 10, cooler 111, pipe 38 and then into the heavy gas oil tank 68, from whence a part is again re-circulated and the excess portion employed as a cracking stock as will be hereinafter more fully explained. The residual oil which passes to the bottom of fractionating tower 11 is permitted to flow through the pipe 28 into the suction side of pump 27 where it is commingled with the light gas oil stock coming from the tanks 127 and 130 through the pipe 126, pump 125 and pipe 124, the flow being controlled by valve 124'. Pump 27 discharges the commingled light gas oil and residual oil through pipe 30, exchanger 31, pipe 32, cooler 33, pipe 44 and then into the residual oil tank 35. The light gas oil from tanks 127 and 130, which is commingled with the residual oil by pump 27, is regulated so that the viscosity of the resultant mixture will be suitable for bunker fuel oil "C", as specified in the Bureau of Mines Bulletin 323 B.

The synthetic gasoline stock and higher boiling distillate or heavy gas oil produced by the cracking of the residual oil passing through the heater coil 50, are separated from the viscous residual oil in the lower section of the fractionating tower 11, and the synthetic gasoline stock is separated from the heavy gas oil stock in the upper section of said fractionating tower 11, passing out through pipe 12 and then into cooling coil 13 where this separated, synthetic gasoline stock is condensed and passes through the pipe 15 into the storage tank 16.

The heavy gas oil as it collects in tank 68 passes in a regulated continuous flow through pipe 69 and then into the suction side of pump 66, controlled by the valve 67'. Pump 66 discharges the heavy gas oil stock through pipe 65, valve 65', valve 65'', heat exchanger 9 and heater coil 116. Arrangements are made so that a part of the oil stream before passing through heat exchanger 9 may be introduced into the oil stream as it leaves the heating coil 116, which is accomplished by partly opening valve 117', thereby permitting a regulated part of the oil stream to pass through the pipe 117 and into the pipe 120 where it is commingled with the cracked oil leaving the heating coil 116, thereby lowering the temperature of the mixed oil stream below an active cracking temperature. Also, arrangements are made for bypassing the heat exchanger 9 or diverting a portion of the oil stream through the pipe 122 by opening valve 122' and closing, or partly closing, valve 65''. The oil stream passing through the heater coil 116 is maintained under a pressure sufficient to prevent substantial vaporization therein (500 to 2000 pounds) and is heated to a temperature sufficient to obtain the maximum yield of synthetic gasoline stock, preferably the oil leaving the coil is maintained at a temperature of approximately 840 to 880 degrees F. and is reduced to a temperature of approximately 750 to 800 degrees F. or lower by the introduction of the cooler oil. The cracked oil commingled with the introduced oil passes in a continuous stream flow from the heating coil 116 through heat exchanger 9, pipe 37, pressure regulating and discharge valve 37' and into the lower section of fractionating tower 59 wherein a synthetic gasoline stock and a heavy gas oil stock are separated as heretofore described.

While the process herein described is well adapted for carrying out the object of the invention, it is to be understood that various changes and modifications may be made without departing from the spirit of the invention, and the invention includes all such changes and modifications as come within the scope of the appended claims.

What I claim is:

1. A process of producing a maximum percentage of gasoline boiling point stock and a residuum of marketable fuel oil quality from a crude petroleum oil, comprising, separately separating by distillation and fractionation gasoline boiling point stock and a higher boiling light gas oil stock from a crude petroleum oil; separately separating by a second distillation and fractionation a light and a heavy gas oil fraction and a synthetic gasoline boiling point stock, from the crude petroleum oil residuum resulting from the first distillation and a cracked petroleum oil continuously introduced at a distillation temperature into a fractionating tower, said cracked petroleum oil being continuously produced by cracking the heavy gas oil stocks

collected from the said second distillation step and from a subsequent cracking and distillation step of the residual oil produced in the said second distillation step, and then reducing the viscosity of the residual oil after the final distillation by commingling the same with a light gas oil separated by the first distillation.

2. A process of producing a maximum percentage of gasoline boiling point stock and a residuum of marketable fuel oil quality from a crude petroleum oil, comprising, separately separating by distillation and fractionation gasoline boiling point stock and a higher boiling light gas oil stock from a crude petroleum oil; separately separating by a second distillation and fractionation a light and a heavy gas oil fraction and a synthetic gasoline boiling point stock, from the crude petroleum oil residuum resulting from the first distillation and a cracked petroleum oil continuously introduced at a distillation temperature into a fractionating tower, said cracked petroleum oil being continuously produced by cracking the heavy gas oil stocks collected from the said second distillation and from a subsequent cracking and distillation of the residual oil produced in the said second distillation, and then reducing the viscosity of the residual oil after the final distillation by commingling the same with a cracked light gas oil separated by the second distillation.

3. A process of producing a maximum percentage of gasoline boiling point stock and a fuel oil which will not have a viscosity greater than 300 seconds at 122 degrees F. by the Saybolt furol viscosimeter, comprising separately separating by distillation and fractionation the naturally occurring gasoline boiling point stock and a higher boiling light gas oil stock from a crude petroleum oil; separately separating by a second distillation and fractionation, a synthetic gasoline boiling point stock, a cracked light gas oil and a heavy gas oil stock, from a cracked petroleum oil and the petroleum oil residuum resulting from the first distillation, said cracked petroleum oil being continuously produced by cracking the heavy gas oil stocks collected from said second distillation and from a subsequent cracking and distillation of the residual oil produced in the said second distillation, and then reducing the viscosity of the residual oils after the final distillation, to the required degree, by commingling the same with a mixture of the light gas oil stocks separated by the first and second distillations.

4. A process of producing a maximum percentage of gasoline boiling point stock and a fuel oil which will not have a viscosity greater than 300 seconds at 122 degrees F. by the Saybolt furol viscosimeter, comprising, separately separating by distillation and

fractionation the naturally occurring gasoline boiling point stock and a higher boiling distillate from a crude petroleum oil; separately separating by a second distillation and fractionation, a synthetic gasoline boiling point stock, a cracked light gas oil and a heavy gas oil stock, from a cracked petroleum oil and the petroleum oil residuum resulting from the first distillation, said cracked petroleum oil being continuously produced by cracking the heavy gas oil stocks collected from said second distillation and from a subsequent cracking and distillation of the residual oil produced in the said second distillation, and then reducing the viscosity of the residual oils after the final distillation, to the required degree, by commingling the same with the cracked light gas oil separated by the second distillation.

5. A continuous process of producing a maximum percentage of gasoline boiling point stock and a fuel oil which will have a viscosity substantially not greater than 300 seconds at 122 degrees F. by the Saybolt furol viscosimeter, comprising, separately separating by continuous distillation and fractionation, the naturally occurring gasoline boiling point stock and a higher boiling light gas oil stock, from a crude petroleum oil; separately separating and collecting by a second continuous distillation and fractionation operation, synthetic gasoline boiling point stock, a cracked light gas oil stock and a heavy gas oil stock, from a cracked oil continuously produced from heavy gas oil stocks, and the petroleum oil residuum resulting from the first distillation; continuously cracking the resultant residuum separated by the said second distillation operation under a pressure sufficient to prevent substantial vaporization, at a cracking temperature; then separately separating by fractionation the synthetic gasoline boiling point stock produced and a heavy cracked gas oil stock from the cracked residuum, and finally reducing the viscosity of the residual oil from the said last named fractionation, by commingling the same with a mixture of the light gas oil stock separated by the first and second distillations.

6. A continuous process of producing a maximum percentage of gasoline boiling point stock and a fuel oil which will have a viscosity substantially not greater than 300 seconds at 122 degrees F. by the Saybolt furol viscosimeter, comprising, separately separating by continuous distillation and fractionation, the naturally occurring gasoline boiling point stock and a higher boiling light gas oil stock, from a crude petroleum oil; separately separating and collecting by a second continuous distillation and fractionation operation, synthetic gasoline boiling point stock, a cracked light gas oil stock and a heavy gas oil stock, from a cracked oil con-

tinuously produced from heavy gas oil stocks, and the petroleum oil residuum, resulting from the first distillation; continuously cracking the resultant residuum separated by the said second distillation operation under a pressure sufficient to prevent substantial vaporization at a cracking temperature; then separately separating by fractionation, the synthetic gasoline boiling point stock produced and a heavy cracked gas oil stock from the cracked residuum and finally reducing the viscosity of the residual oil from the said last named fractionation, by commingling the same with the light cracked gas oil stock, separated by the second distillation.

7. A process of producing a maximum percentage of heavy gas oil stock suitable for the production of synthetic gasoline, comprising, separately separating by distillation and fractionation, the natural gasoline boiling point stock and a higher boiling light gas oil stock from crude petroleum oil, separately separating by a second distillation and fractionation, synthetic gasoline boiling point stock, a light and a heavy gas oil stock, from cracked petroleum oil and the petroleum oil residuum resulting from the first distillation, continuously introduced into a fractionating tower at a distillation temperature, said cracked petroleum oil being continuously produced by cracking the heavy gas oil stock produced in the operations; passing the residual oil from this second distillation and fractionation operation through a heating coil at a temperature sufficient to bring the oil to a cracking temperature maintained at a pressure sufficient to prevent any substantial vaporization thereof; continuously introducing into the oil stream, leaving the heating coil a cool mixture of the heavy gas oil stock separated by the second distillation and from the distillation step of the cracked residuum, in quantities sufficient to lower the temperature of the oil stream below a cracking temperature of approximately 750 degrees F.; separately separating by fractionation the synthetic gasoline boiling point stock and the heavy gas oil stock produced by the said cracking operation, from a viscous residual oil and then commingling the said viscous residual oil resulting from the said last named fractionation operation with the light cracked gas oil separated by the second distillation to produce a fuel oil with a viscosity substantially not greater than 300 seconds at 122 degrees F., by the Saybolt furol viscosimeter.

8. A process of producing a maximum percentage of heavy gas oil stock suitable for the production of synthetic gasoline and a residuum or fuel oil which will comply with the specifications for bunker fuel oil "C", comprising, separately separating by distillation and fractionation, the natural gasoline boiling point stock and a higher boiling light gas oil stock from the crude petroleum oil, separately separating by a second distillation and fractionation, synthetic gasoline boiling point stock, a light and a heavy gas oil stock, from cracked petroleum oil and the petroleum oil residuum resulting from the first distillation, continuously introduced into a fractionating tower at a distillation temperature, said cracked petroleum oil being continuously produced by cracking the heavy gas oil stock produced in the operations; passing the residual oil from this second distillation and fractionation operation through a heating coil at a temperature sufficient to bring the oil to a cracking temperature maintained at a pressure sufficient to prevent any substantial vaporization thereof; continuously introducing into the oil stream, leaving the heating coil a cool mixture of the heavy gas oil stock separated by the second distillation and from the distillation step of the cracked residuum, in quantities sufficient to lower the temperature of the oil stream below a cracking temperature of approximately 750 degrees F.; separately separating by fractionation the synthetic gasoline boiling point stock and the heavy gas oil stock produced by the said cracking operation, from a viscous residual oil and then commingling the said viscous residual oil resulting from the said last named fractionation operation with the light cracked gas oil separated by the second distillation to produce a fuel oil with a viscosity substantially not greater than 300 seconds at 122 degrees F., by the Saybolt furol viscosimeter.

9. A process of producing a maximum yield of gasoline boiling point stock from a crude petroleum oil, comprising, separately separating by distillation and fractionation the natural gasoline stock and a higher boiling light gas oil stock, from a crude petroleum oil, then separately separating by a second distillation and fractionation operation, a heavy gas oil stock, a synthetic gasoline stock and a cracked light gas oil stock, from the residual oil separated in the first distillation step and an introduced cracked petroleum oil, said cracked petroleum oil being simultaneously and independently produced by cracking the heavy gas oil stocks collected from the distillation steps of the process; then cracking the residual oil obtained from the second distillation step and separating by distillation and fractionation a synthetic gasoline stock and a heavy gas oil stock, and finally commingling the residual oil from the last distillation step with a light gas oil stock from the first and second distillation steps.

10. A process of producing a maximum percentage of gasoline boiling point stock and a fuel oil which will not have a viscosity

- greater than 300 seconds at 122 degrees F. by the Saybolt furol viscosimeter, comprising, separately separating by distillation and fractionation the naturally occurring gasoline 6 boiling point stock and a higher boiling light gas oil from a crude petroleum oil; separately separating by a second distillation and fractionation operation a heavy gas oil stock, a synthetic gasoline boiling point stock, and a 10 light cracked gas oil stock, from the petroleum oil residuum resulting from the first distillation operation and a cracked petroleum oil, this said cracked petroleum oil being simultaneously and independently produced by 15 cracking the heavy gas oil stocks collected from the distillation steps of the process; then cracking the residuum resulting from the said second distillation step, separately separating therefrom synthetic gasoline boiling point 20 stock and a heavy gas oil stock and then reducing the viscosity of the resultant residual oil to the required degree by commingling the same with the light gas oil derived from the first and second distillation steps.
- 25 11. A process of producing a maximum percentage of gasoline boiling point stock and a fuel oil which will comply with the specifications for bunker fuel oil "C," comprising, heating a residual oil from which 30 the gasoline stock and light gas oil have been separated by a distillation operation, to a distillation temperature, passing said heated residual oil into a fractionating tower along with hot cracked petroleum oil coming from 35 a cracking system, separately by distillation a synthetic gasoline stock, a light cracked gas oil stock and a heavy gas oil stock; then cracking the residuum resulting from the second distillation operation, separately sepa- 40 rating therefrom by fractionation synthetic gasoline boiling point stock and a heavy gas oil stock and then reducing the viscosity of the residual oil after the said last fractionation step, to the required degree, by com- 45 mingling the same with the light cracked gas oil stock derived from the distillation step first mentioned. 105
12. A process of producing a maximum percentage of gasoline boiling point stock 50 and a fuel oil which will not have a viscosity greater than 300 seconds at 122 degrees F. by the Saybolt furol viscosimeter, comprising, separately separating by distillation and fractionation the naturally occurring gaso- 55 line boiling point stock and a higher boiling light gas oil from a crude petroleum oil; separately separating by a second distillation and fractionation operation a heavy gas oil stock, a synthetic gasoline boiling point 60 stock, and a light cracked gas oil stock, from the petroleum oil residuum resulting from the first distillation operation and a cracked petroleum oil, said cracked petroleum oil being simultaneously produced by cracking 65 a petroleum oil previously produced in the 110
- process, which is introduced directly into a fractionating tower in a heated condition as it comes from a cracking system along with the said petroleum oil residuum; then crack- 70 ing the residuum resulting from the said sec- 75 ond distillation step, separately separating therefrom synthetic gasoline boiling point stock and a heavy gas oil stock and then re- 75 ducing the viscosity of the resultant residual oil to the required degree by commingling the same with the light gas oil derived from the first and second distillation steps. 80
13. A process of treating crude petroleum oil, comprising, separately separating by dis- 85 tillation and fractionation gasoline boiling point stock and a higher boiling light gas oil stock from a crude petroleum oil; separately separating by a second distillation and fractionation a light and a heavy gas oil fraction and a synthetic gasoline boiling point stock, from the crude petroleum oil residuum resulting from the first distillation and a cracked petroleum oil continuously introduced at a distillation temperature 90 into a fractionating tower, said cracked pe- 95 troleum oil being continuously produced by cracking the heavy gas oil stocks collected from the said second distillation step and from a subsequent cracking and distillation step of the residual oil produced in the said second distillation step. 100
